UNITED STATES PATENT OFFICE.

SYLVESTER L. GOOKIN, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FASTENER-SETTING MACHINE.

1,283,732.

Specification of Letters Patent.

Patented Nov. 5, 1918.

Application filed April 10, 1916. Serial No. 90,124.

To all whom it may concern:

Be it known that I, SYLVESTER L. GOOKIN, a citizen of the United States, residing at Boston, in the county of Suffolk and State 5 of Massachusetts, have invented certain Improvements in Fastener-Setting Machines, of which the following description, in connection with the accompanying drawings, is a specification, like reference characters on 10 the drawings indicating like parts in the several figures.

This invention relates to machines for setting fasteners such as eyelets or lacing hooks in the uppers of boots or shoes or other sheet 15 material.

An object of the invention is to provide improved work feeding mechanism for fastener setting machines wherein the feeding tool is mounted in a swinging head. In 20 such machines it is customary to straighten the feeding path by shifting the feeding tool radially during the movement of the head so that the work may be advanced in a substantially straight path instead of a curved 25 path which would be objectionable, particularly in setting fasteners with a wide spacing. The mechanism of my invention accomplishes the desired results in a new and improved manner. To this end a feature 30 of the invention consists in mechanism responsive to the swinging movement of the head for shifting the head to straighten the feeding path of the tool.

As herein shown the supporting means for 35 the head includes an eccentric journal and connections are provided between the head and the journal so that the journal is turned to shift the head bodily in the desired direction when the head is swung in the feeding 40 operation. Such a construction presents the advantages of simplicity and accuracy of operation without objectionably increasing the weight of the moving parts and consequently the inertia of the machine.

45 Other features of the invention relate more particularly to machines for handling two or more layers of sheet material, as for example, the two quarters of an upper, or the lining and outer part of an upper when 50 treated separately as in setting invisible eyelets. In this connection an important feature of the invention consists in a sta-

tionary intermediate plate arranged to support, between two layers of sheet material, the upsetting or punching dies which co- 55 operate with the movable punching and eyelet inserting tools. This construction, certain features of which are equally applicable to either single or duplex machines, is advantageous because it eliminates the tendency to displace the work sometimes caused by the movement of an intermediate plate in case the latter encounters any obstruction such, for example, as a tongue which, in certain styles of boots, it is customary to 60 stitch to one quarter of the shoe. Another advantage incident to this construction is that the work may be punched and eyelets set at a point much closer to a line of stitching than has been possible in machines wherein an intermediate plate is moved perpendicularly to the line of fasteners. In the illustrative construction, the punching and setting tools traverse a single path with respect to the co-acting member, 65 the tubular punch cutting against the central part of an annular upsetting die in the stationary plate.

These and other features of the invention will be best understood and appreciated 70 from the following description of a preferred embodiment thereof selected for purposes of illustration and shown in the accompanying drawings, in which,—

Figure 1 is a view in perspective of the 75 operative instrumentalities of the machine;

Figs. 2, 3, 4 and 5 illustrate successive steps in the punching, setting and feeding operations;

Fig. 6 is a sectional view through the eyelet inserting dies and die plate showing the dies in the position which they occupy at the end of the feeding movement;

Figs. 7 and 8 are plan views of the operative instrumentalities of the machine shown 95 respectively in initial position and in position at the end of the feeding step;

Fig. 9 is a view in perspective of the work controlling means; and

Fig. 10 is a fragmentary view, partly in 100 section, showing the eccentric journal for the feeding head carrier.

The invention is herein illustrated as embodied in an eyeleting machine of the type

disclosed in United States Patent No. 934,066, granted September 14, 1909, on an application of G. Goddu, although it is not limited in its application to that or to any 5 particular type of fastener setting machine. Those parts of the machine not herein illustrated may be considered as similar to the corresponding parts of the machine of said patent. The punching and setting tools, as 10 in the machine of the patent, are mounted to slide longitudinally in bearings formed in the upper and lower branches of a forked head 6 pivotally connected by means of a spindle 5 to one arm of a bell crank lever 4. 15 The lever 4 is mounted upon a portion of the stationary machine frame 2 in a manner to be presently described. The oppositely disposed punches 8 are mounted in parallel relation to and in the rear of the oppositely 20 disposed eyelet sets 10 and are successively operated by hammer levers 12, one of which is shown in Fig. 1 and the other of which corresponds in shape but is concealed from view in the figures of the present drawings. 25 These hammer levers are operated in the proper timed relation by a cam on the main shaft 14 of the machine as fully explained in the patent above identified.

The punches 8 and sets 10 coöperate successively with a combined punching and upsetting die 16 mounted near the outer edge of a thin stationary plate 18. The plate 18 is constructed and arranged to be inserted between the two layers of work operated 35 upon by the machine, one layer being guided across its upper surface and the other layer across its lower surface. Normally stationary but yielding presser feet 20 disposed upon opposite sides of the plate 18 serve to 40 hold the work in position upon the surfaces of the plate 18 but permit it to be advanced in the feeding operation. The plate 18 has a rearwardly extending shank which is stationarily but adjustably secured to the machine frame 2. The presser feet 20 are supported by a block 22 which is clamped upon the shank of the stationary plate 18 and which also carries edge gages 24 which extend transversely along the rear edge of the 45 plate and serve to determine the distance between the line of eyelets and the edge of the work.

In initial position the head 6 is located so that the punches 8 are disposed in alignment 55 with the combined punching and upsetting die member 16 and the punches are operated by the hammer levers 12 while the head remains in this position. The punches have an interior diameter slightly larger than the 60 center part of the member 16 and when operated cut against the curved annular surface of said center part. The head 6 is then shifted rearwardly to bring the sets 10 into the position previously occupied by the

punches. This movement of the head toward the rear is effected by an oscillation of the bell crank lever 4 under the actuation of a cam 26 on the shaft 14. In this movement the sets are brought into operative relation with the hammer levers 12 and the latter are 70 then operated to force the sets toward the stationary upsetting die 16 to insert an eyelet in each layer of the work. 65

After the setting operation has taken place the sets are retracted slightly and the head 6 is moved transversely toward the left to effect the feeding operation. This feeding movement of the head is effected by the cam 28 on the shaft 14 acting through a cam lever 30 and a pair of transmission links 32 80 extending between the forward end of the cam lever 30 and the head 6. A spacing lever 34 is connected to the links 32 in such manner as to control the effective movement transmitted to the head 6 and so regulate the 85 extent of feeding movement.

It will be apparent that when the feeding movement of the head 6 takes place the head swings about the axis of the spindle 5 and consequently, if there were no other means 90 affecting the movement of the head, the path of the setting dies by which the work is fed would be along the arc of a circle described about the axis of the spindle 5 as a center. In order to straighten the feeding path 95 means are provided for shifting the head 6 forwardly during its transverse movement. One specific form of mechanism for effecting this movement is herein shown and will now be described. The bell crank lever 4 which carries the head 6 is mounted to turn about journals 36 formed eccentrically upon the ends of a journal member mounted in bearings in a portion of the machine frame, see Fig. 10. At its upper end an arm 40 is secured to the 100 journal member 38 and by it the said member may be turned and the eccentric journals 36 thrown in the proper direction to advance the cam lever 4 and the head 6 so that the movement of the sets 10 is in a substantially 105 straight line path. The arm 40 is turned by the movement of the head 6 itself and to this end is connected by a link 42 to a point upon the head at a point between its axis and the bearing for the sets. It will thus 110 be seen that the turning of the eccentric journal member is responsive to the swinging movement of the feeding head 6, varying in amount in accordance with the extent 115 of the feeding movement and thus compensating for the rearward movement of the head which would be caused by its movement about the axis 5 in the absence of such provision.

The sets 10 are provided with the usual 125 yieldingly mounted center spindles 46 which serve first to position eyelets presented from the raceways, not shown, and then to assist

in the feeding operation by engaging the barrels of the clenched eyelets while the head 6 is moved transversely. In the feeding movement the ends of the spindles 46 remain in engagement with the opposite faces of the stationary plate 18 as shown in Fig. 6. There is therefore no possibility of the work slipping from the feeding tools and the danger of uneven feeding of the two 10 layers of work is so eliminated.

The operation of the machine will be apparent from the foregoing description but may be outlined briefly with reference to Figs. 2 to 5 as follows:—One layer of the 15 work, or one quarter of the shoe, is inserted beneath the uppermost presser foot 20 and the upper surface of the stationary plate 18 while the other layer of the work or quarter of the upper is similarly inserted between 20 the lower presser foot 20 and the lower surface of the plate 18. The edges of both pieces are brought into engagement with the edge gages 24 and are positioned so as to bring the points at which the first holes 25 are to be punched into alignment with the combined punching and setting die 16, and consequently into alignment with the oppositely disposed punches 8. The machine is then started and the punches are immediately 30 operated as shown in Fig. 3 to form a hole in the upper layer 50 and the lower layer 52 of the work. It will be noticed that the punching operations take place independently so that holes of different sizes 35 may be formed if desired in the two layers of the work.

At the conclusion of the punching operation the hammer levers 12 are retracted, the punches withdrawn and the head 6 shifted 40 rearwardly to bring the sets into alignment with the previously punched holes. It will be noticed that during these steps of the cycle there is no movement of the plate 18 between the two layers of work but that 45 this plate, the edge gages and the presser feet all remain stationary. Eyelets are then presented to the spindles 46 of the sets 10 by raceways, not shown, and the sets are then operated by the hammer levers 12 to insert 50 eyelets into the previously formed holes and clinch them against the opposite sides of the upsetting die member 16. This step of the cycle is illustrated in Fig. 4.

At the conclusion of the setting operation 55 the sets are slightly retracted to relieve the pressure upon the stationary upsetting member 16 and the head 6 is moved transversely to feed the work. During this operation the ends of the spindles 46 remain in yielding engagement with the opposite faces of the stationary plate 18 and are moved transversely in sliding contact with the surfaces. Figs. 5 and 6 illustrate the machine parts in the positions occupied at the end of

the feeding operation. During this feeding 65 operation the turning movement of the eccentric journal member 38 throws the head 6 forwardly causing the feeding tools to move along a substantially straight line path. At the conclusion of the feeding operation the 70 sets 10 are retracted and the parts of the machine returned to their initial positions shown in Fig. 2.

Having thus described my invention, I claim as new and desire to secure by Letters 75 Patent:

1. A fastener setting machine having, in combination, a pivotally mounted carrier, a feeding head pivoted thereto, and means for shifting the axis of the carrier during the 80 swinging feeding movement of the head to straighten the feeding path.

2. A fastener setting machine having, in combination, a pivotally mounted carrier, a swinging feeding head on the carrier, and 85 means actuated by the swinging movement of the feeding head for shifting the axis of the carrier.

3. A fastener setting machine having, in combination, an oscillatory carrier, a swinging feeding head on the carrier, and means 90 responsive to the movement of the feeding head for shifting the axis of the carrier to straighten the feeding path.

4. A fastener setting machine having, in 95 combination, a carrier, a journal for the carrier having an eccentric portion, a swinging feeding head on the carrier, and means responsive to the movement of the head for turning the journal to shift the carrier 100 bodily during the feeding operation.

5. A fastener setting machine having, in combination, a frame, a spindle rotatably mounted in the frame and having eccentric journals projecting from the frame, a carrier arranged to oscillate about said journals, a feeding head connected to the carrier, and mechanism for turning the spindle during the feeding operation to cause said eccentric journals to shift the carrier to 110 straighten the feeding path.

6. A fastener setting machine having, in combination, a spindle having eccentric journals, a carrier arranged to oscillate upon said journals, a feeding head supported by the 115 carrier, and connections between the head and spindle for turning the spindle when the head is moved to feed the work.

7. A fastener setting machine having, in combination, a spindle having eccentric journals, a carrier arranged to oscillate upon said journals, a feeding head supported by the carrier, an arm secured to the spindle, and a link extending between said arm and a point on the feeding head.

8. A fastener setting machine having, in combination, a tubular punch, an inserting die, a combined punching anvil and upset-

ting member, and mechanism for moving the punch toward said member to perforate the work and then moving the inserting die in the same path with respect to said member 5 as that previously traversed by the punch for inserting an eyelet.

9. A fastener setting machine having, in combination, an upsetting die, a punch, an inserting die, and mechanism for supporting 10 said punch and inserting die in laterally displaced relation and for moving first the punch and then the inserting die axially toward said upsetting die to perforate the work and set an eyelet therein.

15 10. A fastener setting machine having, in combination, a combined punching anvil and upsetting member, a punch initially located in alinement with said member and movable toward the member to punch the work, an 20 inserting die arranged to be moved laterally into the position with respect to said member formerly occupied by the punch and then toward said member for inserting an eyelet.

11. A fastener setting machine having, in combination, a combined anvil and upsetting member, a head movable relatively to 25 said member to carry first a punch and then an inserting die into alinement therewith, and means for operating first the punch 30 and then the die while said member remains at rest.

12. A fastener setting machine having, in combination, a member having a central cutting block surface and a concentric concaved upsetting surface, a tubular punch arranged to coöperate with said central surface in perforating the work, and a set arranged to coöperate thereafter with the upsetting surface to insert an eyelet.

40 13. A fastener setting machine having, in combination, a stationary plate having a combined anvil and upsetting member thereon, a punch arranged to coöperate with said member to perforate the work, and a 45 set having a yielding spindle movable to feed the work and to draw the end of the spindle over the surface of the stationary plate.

50 14. A fastener setting machine having, in combination, a stationary plate projecting so as to leave free passage for the work beneath it and having a continuous work supporting surface upon its underside, a presser foot acting to hold the work up against a part 55 of said surface, an upsetting die let into another part of the surface, and means for feeding the work from the presser foot to the upsetting die across the surface of the plate.

60 15. A duplex fastener setting machine having, in combination, a stationary intermediate plate, setting dies movable toward opposite sides of the plate to insert eyelets in both quarters of a shoe upper, and means

for moving said dies transversely across opposite surfaces of the stationary plate. 65

16. A duplex fastener setting machine having, in combination, a thin stationary plate having an outer transverse edge and a double faced combined punching and upsetting member disposed adjacent to its edge, and feeding tools movable in contact with the opposite faces of said plate from said device in a direction parallel to the edge of the plate. 70 75

17. A duplex fastener setting machine having, in combination, a thin stationary plate having a double faced upsetting die near its outer edge, oppositely disposed sets having each a yielding spindle, means for 80 operating the sets first to insert a pair of eyelets and then to feed the work by drawing the spindles across the surfaces of the plate while they engage respectively the clenched eyelets. 85

18. A duplex fastener setting machine, having, in combination, a thin stationary plate having a double faced combined punching block and upsetting die, a head having arms extending upon opposite sides 90 of the plate, a punch and a set mounted side by side in each arm of the head, means for operating the punches, means for shifting the head first to carry the sets into the positions previously occupied by the 95 punches and subsequently to feed the work across the opposite faces of the stationary plate.

19. A duplex fastener setting machine, having, in combination, a frame having a 100 stationary plate projecting therefrom, presser feet arranged to coact with portions of the opposite surfaces of the plate, a double faced upsetting die let into the plate at one side of the presser feet, and feeding 105 means arranged to engage the work in alinement with the upsetting die and feed the work between the presser feet and the plate.

20. A duplex fastener setting machine, having, in combination, a stationary plate 110 having a continuous work positioning surface on either side, an edge gage located upon each surface at the rear thereof, oppositely disposed punches, and means movable yieldingly across opposite surfaces 115 of the plate to feed simultaneously two layers of upper material with the edge of each against its respective edge gage.

21. A fastener setting machine, having, in combination, a swinging head, a work 120 feeding tool therein, means for supporting the head including an eccentric journal, and means responsive to the swinging movement of the head to turn the eccentric journal.

22. A fastener setting machine, having, 125 in combination, a combined punching and upsetting die member having a central projection, a tubular punch having an interior

diameter slightly larger than the diameter of the projection, a set, and means for alternately advancing the punch and set toward said member first to punch the work 5 and then to insert an eyelet.

23. A fastener setting machine having, in combination, a feeding head, means for supporting said head for pivotal movement

comprising a journal, and means responsive to the movement of the feeding head 10 for shifting the axis of said journal during the pivotal feeding movement of the head to straighten the feeding path.

In testimony whereof I have signed my name to this specification.

SYLVESTER L. GOOKIN.
